US00D862494S

(12) **United States Design Patent** (10) Patent No.: **US D862,494 S**
 Kaminer et al. (45) Date of Patent: ** Oct. 8, 2019

(54) **DISPLAY SCREEN OR PORTION THEREOF WITH GRAPHICAL USER INTERFACE**

(71) Applicant: **Delos Living LLC**, New York, NY (US)

(72) Inventors: **Barrett Brod Kaminer**, New York, NY (US); **Max Andrew Pollinger**, New York, NY (US); **Tarynne Blake Lopez**, Cranford, NJ (US); **dingane Richard St Arromand**, New York, NY (US); **Shivaun Ryan**, South Yarra (AU); **Chris David Hall**, Narre Warren South (AU); **Shaun Benson Stewart**, New York, NY (US)

(73) Assignee: **Delos Living LLC**, New York, NY (US)

(**) Term: **15 Years**

(21) Appl. No.: **29/628,130**

(22) Filed: **Dec. 1, 2017**

(51) LOC (12) Cl. **14-04**

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface.

The evenly spaced dashed lines illustrate a display screen or portion thereof and form no part of the claimed design. The dot-dash lines illustrate a boundary line and form no part of the claimed design.

1 Claim, 1 Drawing Sheet
